UNITED STATES PATENT OFFICE.

EMIL GRANTZOW, OF DRESDEN, GERMANY.

AUTOMATIC PENCIL-SHARPENER.

1,075,971.

Specification of Letters Patent. Patented Oct. 14, 1913.

Application filed March 15, 1910. Serial No. 549,552.

To all whom it may concern:

Be it known that I, EMIL GRANTZOW, a citizen of the German Empire, and resident of Dresden, Germany, have invented certain new and useful Improvements in Automatic Pencil-Sharpener, of which the following is a specification.

This invention relates to a pencil holder for use in automatic pencil sharpeners, adapted to hold pencils of different thickness and to a device in connection therewith, for adjusting the length of the pencil point.

The improvement may be used in connection with a pencil sharpener having a rotatable knife and a step by step rotation of the pencil holder and consists, primarily, of two spring controlled slides, arranged one above the other in planes at right angles to the axis of the pencil holder, each slide having an opening of larger dimension than the thickness of the largest pencil intended to be sharpened, and arranged to aline or coincide for the insertion of the pencil to be held therein.

The adjusting device for the length of the pencil point comprises a slide, movable in a plane located somewhat higher than the one on which the pencil point would normally rest, so that the pencil point is made correspondingly shorter.

The accompanying drawing illustrates in Figure 1 a front view of a pencil sharpener, in Fig. 2 a vertical cross-section in a plane at right angles to that of Fig. 1, and in Fig. 3 a plan view of Fig. 1. Fig. 4 is a vertical sectional view of the holder detached and showing the gripping devices in one position. Fig. 5 is a plan view thereof with the gripping devices in a similar position. Fig. 6 is a sectional view similar to Fig. 4 with the grippers in a spread or open position. Fig. 7 is a plan view similar to Fig. 5 with the grippers in the position shown in Fig. 6.

The body portion *a* of the pencil sharpener carries the rotatable knife *b*, in a manner well known in the art. This body portion is provided with the opening *d* through which the pencil extends into the cutting plane. A toothed wheel *e* is arranged on the pencil holder *c* and adapted to be rotated in the usual way of pencil sharpeners of this type, by suitable devices on the rotatable cutter or its shaft. The pencil is inserted into the pencil holder, extends

through the opening *d* into the cutting plane and rests normally in the recess *f*, forming the lower extension of the opening *d*.

The head of the pencil holder *c* carries in proper recesses, located at diametrically opposite points of the head, two helical springs *g*, arranged to act against flanges of the slides *h*, *h*. These slides are located one immediately above and, preferably, in contact with the other and are movable in planes, substantially at right angles to the axis of the pencil holder, in guide ways, provided for this purpose in the head of the pencil holder. Each of the slides has a jaw *i*, the two jaws forming a clamp for holding, in a shear-like grip, the pencil inserted between the same. It will be seen that the slides *h* are capable of holding a pencil as thin as the opening shown in Fig. 4 or as thick as the one shown in Fig. 5.

The adjusting device for the pencil point consists of the slide *k*, movable in substantially a horizontal plane, located somewhat above the recess *f* of the opening *d*. A pencil, the advance of which is arrested by striking this slide *k*, receives obviously a point, proportionally shorter than a pencil resting in the recess *f*.

What I claim as new and desire to secure by Letters Patent of the United States is:

In combination with a pencil sharpening mechanism, of a chuck rotatably mounted in said mechanism and comprising a chuck body having a bore therein for insertion therethrough of a pencil, superposed grippers disposed in overlapping relation with respect to each other above said body and each having an opening therein, the lower gripper having a downwardly projecting pencil engaging portion extending into and adapted to engage a part of the bore of said body at one point and to arrest opening movement of said gripper, the upper gripper having a pencil engaging portion for engaging the pencil in opposition to said first named portion and projecting through the opening in said lower gripper and into the bore of said body to arrest opening movement of said upper gripper, said upper gripper having an extension projecting in the direction of the pencil closing movement of said gripper, a spring interposed between said extension and said chuck body whereby said upper gripper is actuated to move its pencil engaging portion toward the

engaging portion of the lower gripper, the lower gripper having an extension projecting in the direction of its movement in a direction opposite to the extension of said upper gripper, and a spring interposed between the chuck body and said lower gripper extension for moving the same and its pencil engaging portion toward the pencil engaging portion of said upper gripper,
10 substantially as described.

In testimony whereof I have hereunto signed my name this 9th day of August 1909, in the presence of two subscribing witnesses.

EMIL GRANTZOW.
